VACUUM CLEANER HEAD

Norbert Shaeffer, deceased, late of Hollywood, Calif., by Frances E. Shaeffer, administratrix, Hollywood, Calif.,
assignor to Preco Incorporated, Los Angeles, Calif.,
a corporation of California

Application January 28, 1959, Serial No. 54,360

Term of patent 14 years

(Cl. D9—2)

FIG. 1.

FIG. 2.

FIG. 3.

Fig. 1 is a front perspective view of a vacuum cleaner head showing my new design.

Fig. 2 is a rear perspective view thereof.

Fig. 3 is a bottom perspective view thereof.

The dominant features of my design reside in the portions shown in full lines.

I claim:

The ornamental design for vacuum cleaner head, as shown and described.
